UNITED STATES PATENT OFFICE.

NILS NILSSON, OF NEW YORK, N. Y.

TURBINE MOTOR.

SPECIFICATION forming part of Letters Patent No. 637,818, dated November 28, 1899.

Application filed March 10, 1897. Renewed November 18, 1898. Serial No. 696,784. (No model.)

To all whom it may concern:

Be it known that I, NILS NILSSON, a citizen of the United States, residing in the borough of Brooklyn, city of New York, county of 5 Kings, and State of New York, have invented certain new and useful Improvements in Turbine Motors, of which the following is a specification.

This invention relates to improvements in 10 turbine motors; and it has for its main object the provision of an improved motor of this type in which the force or energy of an expansible fluid under pressure may be used to better advantage and with a higher degree of 15 efficiency than has been the case heretofore to drive a turbine wheel.

In carrying my invention into effect I prefer to employ, in connection with a turbine wheel having blades or buckets against which 20 the motive fluid will be directed, suitable fluid-supplying means embodying, preferably, a plurality of passages of such lengths and cross-section as to facilitate the transformation of a body of gaseous fluid under high 25 pressure into a jet or stream of relatively-small cross-section in which most of the pressure of the fluid is exerted lengthwise of the jet as velocity and comparatively little pressure is exerted transversely. These jets or 30 streams of fluid transformed into moving bodies of fluid of high velocity and relatively-low transverse pressure may be impelled against the faces of the blades or buckets of the turbine wheel in such a manner that sub- 35 stantially all of the force or energy of each jet will be transmitted to a driven member, preferably approximately perpendicular to the path of the moving stream, in order to utilize to the best advantage the longitudinal 40 energy or pressure of the jet. In the preferred construction each jet of fluid will be directed against one wall of a fluid-receiving chamber in a turbine wheel of proper construction, and the receiving end of this fluid- 45 receiving chamber should be as close as possible to the discharge end of the passage through which the jet is delivered to the turbine. The cross-sectional area of the fluid-receiving chamber coöperating with any such 50 passage should be approximately that of the discharge end of such passage for the purpose of conserving that portion of the energy of

the jet or stream which is exhibited as transverse pressure and which when the fluid is further expanded may be capable of doing 55 effective work as a wheel-propelling medium. Hence in the construction shown the cross-sectional areas of the receiving ends of the several fluid-chambers of the turbine wheel, though somewhat greater than the 60 corresponding areas of the discharge ends of the fluid-passages through which the jets are delivered, are yet approximately the same, and such chambers may be advantageously so formed as to taper toward their 65 discharge ends, and thus conserve such transverse energy of the jet or stream until the fluid of the stream shall have reached a point where such fluid can be expanded effectively 70 for the purpose of imparting an additional impulse to the wheel for rotating the latter. This expansion of the fluid of the jet is effected at the receiving end of a fluid-discharging chamber opening into a fluid-receiving chamber and having a receiving end of 75 greater cross-sectional area than that of the discharge end of such receiving-chamber. Hence it will be apparent that by reason of this construction the fluid will expand suddenly when it reaches the receiving end of 80 the discharge-chamber and will react upon the walls of the latter, the energy exerted by such reaction serving as a means for imparting an additional impulse to the wheel in the direction of its rotation for accelerating the 85 speed of movement of the latter.

It will be evident, therefore, that one of the main features of this invention is the employment of a turbine wheel having fluid-receiving and fluid-discharging chambers in which 90 the receiving end of each discharge-chamber is of greater area than the discharge end of the corresponding fluid-receiving chamber into which such discharge-chamber opens. It will be seen, moreover, that in the preferred 95 construction not only is each discharge-chamber dissimilar to the receiving-chamber in point of size, but that such discharge-chamber is also inclined at a different angle to the plane of rotation of the turbine wheel, the 100 best construction being that in which the forward walls of each coöperating pair of fluid-receiving and fluid-discharging chambers form a V-shaped surface. The object of this

is of course to utilize the force or energy of the fluid to the best advantage, both as a jet or stream exerting a direct pressure against the forward wall of the fluid-discharging chamber and as an expanding fluid exerting by reaction due to transverse expansion an additional force on the forward face or wall of the fluid-discharging chamber to accelerate the rotation of the wheel. Owing to the 5 oblique disposition of the discharge-chamber relative to the plane of rotation of the wheel and to the fluid-receiving chamber coacting therewith, substantially all of the energy of the jet exerted in longitudinal direction and 10 also that exerted transversely on the expansion of the jet will be utilized either directly or by reaction before the fluid escapes from the discharge end of the fluid-discharging chamber and is permitted to pass out through 15 a suitable exhaust. It will be noted, moreover, that not only does each fluid-receiving chamber taper toward its discharge end, but that each fluid-discharging chamber gradually widens toward its discharge end, the 20 walls thereof diverging in order to permit a continuous and gradual expansion after the first sudden expansion of the fluid on entering the discharge-chamber, this gradual expansion assuring the utilization of nearly all 25 of the energy which may be exhibited as transverse pressure.

While, as has been stated, the forward face of each fluid-receiving chamber is preferably disposed obliquely to the plane of rotation of 30 the wheel, and while the supply-passages by means of which the fluid is delivered to the receiving-chambers of the wheel are also oblique to such plane of rotation, yet said passages and chambers have different degrees of 35 obliquity, the passages being inclined at a more acute angle to the plane of rotation than said chambers, and these supply-passages will also be disposed tangentially to the path of movement of the wheel.

40 As it is desirable to provide some means for varying the supply of fluid to the wheel to permit the latter to be run at a high or at a considerably lower rate of speed, I deem it important to provide in connection with the 45 fluid-supplying means suitable fluid-controlling means for regulating the flow of fluid delivered to the rotary-driven member or wheel proper. In this case the fluid-controlling means which I prefer to employ will be operative for opening or closing communication 50 between the fluid-supplying means and some or all of the receiving-chambers of the wheel, and usually a valve, preferably oscillatory, shiftable between two extreme positions and 55 having a plurality of ports adapted to open or close such communication in accordance with the position of the valve will be employed for this purpose. Here the valve used has two dissimilar sets of supply-ports, one 60 of which sets will coöperate at one time, while another set will coöperate at another time with more or less of such passages, the two

sets being selected alternatively, the one to turn on the fluid through all of the supply-passages and the other to turn on the fluid 70 through only a portion of such passages.

When the motor is run at too high a rate of speed, the rate of rotation of the driven member or wheel should be reduced, and usually this will be accomplished by means of an automatic governor controlled by the driven member and governing the operation of the fluid-controlling means or cut-off valve. In this case when the wheel is running at high speed the governor will shift the valve to a position 80 where some only of the fluid-passages will communicate with the fluid-supply, and here such supply will be reduced by one-half by this shifting of the valve. Of course it will be evident that during such shifting movement the supply from all of the open ports will be reduced gradually up to the point of cut-off and that the supply will be turned on gradually to the lesser number of ports by the movement of the valve to its other extreme position.

Other important features of this invention, which need not be more fully referred to at this point, but which will be described in detail hereinafter, relate to the construction of 95 the turbine wheel and to the manner in which it is mounted to yield transversely to the shaft in order to prevent undue strain on the latter in starting under a heavy load or at an increased rate of speed.

100 In the drawings accompanying and forming part of this specification, Figure 1 is a longitudinal sectional elevation of a turbine motor embodying my invention. Fig. 2 is a sectional end elevation of the same with parts removed in order to illustrate the construction more clearly. Fig. 3 is a sectional end elevation of the same, the section being taken in line 33, Fig. 1. Fig. 4 is a sectional end elevation of the same, the section being taken in line 44, Fig. 1, and showing the cut-off valve in one position. Fig. 5 is a similar view of a portion of the same, illustrating said cut-off valve in a different position. Fig. 6 is a transverse section of the motor, the section being taken 110 in line 66, Fig. 1. Fig. 7 is an enlarged sectional plan of a portion of the mechanism, illustrating in detail the manner in which fluid is delivered from the source of supply to the turbine, the section being taken in line 115 77, Fig. 4. Fig. 8 is an enlarged longitudinal section of a portion of the motor, illustrating the manner in which the wheel is mounted on its shaft; and Fig. 9 is a transverse section of the same, the section being taken in line 99, Fig. 8.

120 Similar characters designate like parts in all the figures of the drawings.

125 My improved turbine motor embodies a turbine wheel, such as A, which may be mounted yieldingly on a shaft, such as B, so as to be capable of movement transverse to the shaft to prevent excessive strains upon the parts. In the present case the shaft B is journaled

at one end in a bearing C' in a casing C, which may be supported in a substantially annular frame C², secured in any suitable manner to a base or support, such as D, the opposite end 5 of the shaft B being supported in a bearing in a standard, such as D', rising from the base D. The movement of the shaft B may be transmitted by means of a pulley E to any suitable driven mechanism. In the construction 10 shown the casing C is so made as to form between it and the frame C² an annular space or fluid-chest into which the fluid, which ordinarily will be steam, may be delivered through a proper supply-pipe, such as G. 15 From this fluid-chest the motive fluid may be delivered to the turbine wheel and the flow of the steam or other motive agent properly regulated.

As before stated, the driven member or turbine wheel of the motor is of novel construction and is intended to be so formed as to utilize the force of the expanding fluid to the best advantage. Here the wheel, which is designated in a general way by A and which 25 will preferably be made of a plurality of parts, has a circuit of fluid-receiving chambers in its web A', these chambers being indicated by A². Each of these fluid-receiving chambers preferably intersects the periphery 30 of the web of the wheel and is disposed transversely and obliquely to the plane of rotation of said wheel, the receiving end of said chamber being in this case at one side of the wheel and the discharge end of said chamber being 35 practically in the plane passing through the center of the wheel.

The forward and rearward walls of each chamber A² constitute the walls of the buckets of the wheels and form partitions or blades 40 between the buckets, against which blades the fluid may exert its force. In the construction shown each chamber is not only disposed at an inclination to the plane of rotation of the turbine wheel, but is also angular 45 in cross-section and tapers toward the center of the wheel in order to prevent premature undue expansion of the motive fluid. By making the receiving-chambers angular in cross-section, substantially as shown, a 50 wide face is presented squarely to the action of the jet of fluid, and an impulse of maximum force is received by the wheel on the impact of the jet against such plane face.

The fluid-discharging chambers of the wheel 55 are indicated herein by A³, and these chambers are dissimilar in construction, shape, and position to those shown at A². The principal feature of difference is that the receiving end of the fluid-discharging chamber is of greater 60 area than the discharge end of the fluid-receiving chamber, and as the discharging-chamber opens into and communicates directly with the receiving-chamber a shoulder is formed in the corresponding transverse 65 partition A⁴ at a point between the receiving and discharging chambers. The object of this is, as before stated, to permit the steam

or other fluid to expand quickly in transverse direction as it emerges from the receiving fluid-chamber, and thus to utilize a large percentage of that portion of the force of the fluid which is expanded as transverse pressure, the result being that when fluid expands suddenly at this point in the manner described it will have a reacting-point to act 70 against immediately on entering the fluid-discharging chamber, and the force of the fluid so reacting will be effective to impart an additional impulse to the wheel in the direction in which it is turned, as indicated by 75 the arrow a'. This force, due to the transverse expansion of the steam or other fluid, is of course augmented by the force due to the impact of the jet against the forward wall 80 of the fluid-discharging chamber, this latter 85 force being derived, of course, from the velocity or energy in longitudinal direction of the escaping jet or stream. Another factor which tends to increase the efficiency of the motor and to accelerate the rotation of the 90 turbine wheel is the gradual expansion of the fluid during this passage through the discharging-chamber and after its sudden expansion immediately on entering such chamber, this subsequent gradual expansion being due to the fact that in the preferred construction such fluid-discharging chambers will gradually widen toward their discharge 95 ends, and hence by the time that the fluid is discharged or exhausted from the wheel a 100 very much larger percentage of its energy will have been employed effectively than in turbines as ordinarily constructed.

It will be noticed that the efficiency of the motive fluid as a wheel-propelling medium is 105 very greatly increased by reason of the positions of the fluid-receiving and fluid-discharging chambers relative to each other, each discharging-chamber being in this case disposed at such an angle to the corresponding receiving-chamber as to form therewith a substantially V-shaped passage the walls of which facilitate the reaction of the fluid against the partitions or blades of the wheel to assist in driving the latter forward.

In the preferred construction the wheel A is made in sections, in such a manner that any part can be readily replaced without putting in a whole new wheel. In this case the wheel is made of three main parts, two of which are 110 separate and connected to form the web and the hub of the wheel, while the third part is a rim encircling the web portions of the wheel and preferably shrunk thereon to bind the web portions firmly together. This rim, which 115 is indicated by r, will usually be a circular one and will form here the outer ends of all of the fluid chambers or buckets of the wheel; but said rim will not ordinarily be of the same width as the two connected portions, but instead will overlap only a portion of the web member in which the fluid-discharging chambers are formed, this construction permitting 120 the spent fluid to escape freely both length-

wise of the discharging-chambers and radially of the wheel. One of these web portions is indicated herein by w and contains the fluid-receiving chambers, while the other is indicated by w' and has formed therein the fluid-discharging chambers. Both the fluid-receiving and fluid-discharging chambers of the wheel will preferably intersect the peripheries of said web members, and hence it will be apparent that said chambers may be readily and rapidly cut in the peripheral edges of the respective web portions and properly spaced, the several operations necessary to form these parts being performed most expeditiously by automatic or semi-automatic machinery. Of course one member should contain only the fluid-receiving chambers and the other should contain only the fluid-discharging members, and hence, although the two sets of chambers are entirely dissimilar in size and location with respect to the plane of the wheel, the wheel itself may be constructed at a very low cost by cutting the fluid-chambers entirely through the peripheral portions of the webs from side to side of the latter and then putting the two parts together and properly connecting them afterward, a suitable rim r , also of simple construction, being shrunk around them. Thus a turbine wheel having fluid-receiving and fluid-discharging chambers of peculiar shape and located in a peculiar manner relatively to one another, which chambers could only be formed ordinarily with great difficulty and at heavy expense, can be readily and economically so made and shaped by simply forming the wheel in several parts.

For the purpose of regulating the flow of the steam or other fluid to the turbine wheel I may make use of suitable fluid-controlling means, such as an oscillatory cut-off valve F , which may be an annular valve substantially filling the space within the fluid-chest C^3 , and this valve will usually be a hollow one, the annular space of which will be in connection with the main supply-pipe G through an elongated opening F^2 , which registers with the opening in said supply-pipe in all positions of the valve. This valve F is intended to be oscillatory between two extreme positions for the purpose of controlling the supply of fluid or steam to the turbine wheel, and while this supply may be regulated in many different ways I prefer to employ a controlling-valve, such as F , having a plurality or circuit of supply-ports open at all times to the supply side of the annular space F' in the valve, but some of which at times will be closed to communication with the turbine wheel at the delivery side of the valve, in accordance with the position of the latter. In the present case I prefer to make use of two sets of supply-ports, such as b and c , the former of which contains six ports and the latter three ports, the construction and organization of the parts being such that the valve F may be turned to either one of two extreme positions, in one of which the ports of one set will coöperate with sup-

ply-passages a in the casing C , while in the other position of the valve the other set of ports will coöperate with such supply-passages. The supply-passages a are not only disposed obliquely to the plane of rotation of the wheel A , but also at a more acute angle thereto than are the fluid-receiving chambers A^2 , and in addition said supply-passages are disposed tangentially to the wheel in order to apply the force to the wheels at the points of maximum efficiency or leverage and at the same time permit the wheel, the casing C , containing the supply-passages, and the valve containing the ports b and c to be organized substantially as shown in Fig. 7 and prevent leakage of the steam or other fluid, and hence loss of power. It will be apparent, of course, that the receiving ends of the supply-passages a should be disposed in positions corresponding to those of some of the supply-ports F , and preferably they will be equidistant from one another and will correspond in position to the positions of the ports b , while the ports c may register with alternating supply-passages when the valve is properly turned, at which time communication from the supply-pipe to the intermediate supply-passages a will be prevented. Thus the steam or other fluid may be supplied to the turbine wheel either through all of the supply-passages a or through only half of them to reduce the speed of rotation of the wheel in a manner which will be apparent by referring to Figs. 4 and 5.

The cut-off valve F may be operated in any desired manner; but I prefer to control it automatically by means of a governor g , carried by a suitable portion of the driving mechanism, as by the shaft B , and this governor may be of any suitable type—such, for example, as that shown herein. Said valve may have a pin H , which in this case extends through an elongated slot c' in one side of the frame C^2 , and may be connected at its outer end with a link, such as H' , suitably connected by the governor, it being in this case connected thereto by means of a rod H^2 . If now the turbine wheel is running too fast, the governor will shift the valve so as to open communication between the source of supply and three of the supply-passages a , whereas when the motor is slowed down and is running under a supply from only three such passages the valve may be shifted automatically to open communication to all six of the passages and increase the speed of the wheel.

In order to prevent undue strains upon the several coöoperative parts, I mount the turbine wheel A so that it may be capable of movement transverse to the shaft B , and in the preferred construction said wheel will be supported by springs held on the shaft and having their opposite ends in juxtaposition with the wheel, so that substantially the full length of each spring will lie within the ends of the wheel-hub and may serve to support the wheel. In the construction shown the wheel A has a hub A^5 formed in two parts, in this case these two

hubs being integral with the respective web portions w and w' , and in the ends of this hub I may form recesses, such as A^6 , with the walls of which may engage lugs or tongues, such as 5 I' , formed on collars, such as I, secured in any suitable manner, as by pins I^2 , to the shaft B, as shown in Figs. 1 and 8. The hub A^5 is mounted loosely on the shaft B, and in this portion of the shaft and between the collars I may 10 be formed longitudinal recesses, into which may fit suitable springs, such as the flat springs J, the ends of which may rest against the shaft of the wheel and the central portions of which may engage the walls of the bore of 15 the hub A^5 substantially centrally thereof. In this case the springs J fit at their ends into recesses in the collars I and are so shaped and curved that pressure on the wheel in one direction will be taken up properly by the 20 springs on that side, while the spring or springs on the other side will be relieved. Hence the spring is free to yield transversely to the shaft, according to the direction of the pull on the wheel, and the pressure exerted 25 will be substantially evenly distributed at opposite ends of the wheel to maintain the latter in its proper plane of rotation, this construction dispensing with the use of a long flexible shaft as heretofore used in other motors. Thus 30 undue strains on the shaft B are obviated and the wheel A is enabled to run uniformly at a very high rate of speed.

Steam or other fluid as it issues from the discharge-chambers A^8 may pass into a hood, 35 such as K, secured to the base D and having a large exhaust-opening, as K' .

In order to reduce the friction between the cut-off valve F and its support, I prefer to interpose a ball-bearing between the inner face 40 of the frame C² and the outer face of said valve, these balls being indicated by L and being adjustable in a ball-race in the outer face of the valve by screws L'.

Having described my invention, I claim— 45 1. A turbine wheel having fluid-receiving chambers, and also having fluid-discharging chambers opening, respectively, into the fluid-receiving chambers and each of greater area at its receiving end than the discharge end of 50 the corresponding fluid-receiving chamber.

2. A turbine wheel having fluid-receiving chambers disposed transversely to its plane of rotation, and also having fluid-discharging chambers opening, respectively, into the fluid- 55 receiving chambers and each of greater area at its receiving end than the discharge end of the corresponding fluid-receiving chamber.

3. A turbine wheel having angular fluid-receiving chambers disposed transversely to its 60 plane of rotation, and also having fluid-discharging chambers opening, respectively, into the fluid-receiving chambers and each of greater area at its receiving end than the discharge end of the corresponding fluid-receiving chamber.

4. A turbine wheel having fluid-receiving chambers tapering toward their discharge

ends and disposed transversely to the plane of rotation of the wheel, and also having fluid-discharging chambers opening, respectively, 70 into the fluid-receiving chambers and each of greater area at its receiving end than the discharge end of the corresponding fluid-receiving chamber.

5. A turbine wheel having transverse fluid-receiving chambers disposed obliquely to its plane of rotation, and also having fluid-discharging chambers opening, respectively, into the fluid-receiving chambers and each of greater area at its receiving end than the discharge end of the corresponding fluid-receiving chamber. 75

6. A turbine wheel having transverse fluid-receiving chambers tapering toward their discharge ends and disposed obliquely to the 85 plane of rotation of the wheel, and also having fluid-discharging chambers opening, respectively, into the fluid-receiving chambers and each of greater area at its receiving end than the discharge end of the corresponding fluid-receiving chamber and disposed obliquely to the latter. 90

7. A turbine wheel having transverse fluid-receiving chambers tapering toward their discharge ends and disposed obliquely to the 95 plane of rotation of the wheel, and also having fluid-discharge chambers opening, respectively, into the fluid-receiving chambers and each of greater area at its receiving end than the discharge end of the corresponding fluid-receiving chamber and forming with such fluid-receiving chamber a substantially V-shaped passage. 100

8. In a turbine motor, the combination, with a turbine wheel having fluid-receiving 105 chambers disposed transversely to its plane of rotation, and also having fluid-discharging chambers opening, respectively, into the fluid-receiving chambers and each of greater area at its receiving end than the discharge end of the corresponding fluid-receiving chamber, of fluid-supplying means having supply-passages opening into said fluid-receiving chambers and disposed obliquely to the plane of rotation of the wheel. 115

9. In a turbine motor, the combination, with a turbine wheel having transverse fluid-receiving chambers disposed obliquely to its plane of rotation, and also having fluid-discharging chambers opening, respectively, into the fluid-receiving chambers and each of greater area at its receiving end than the discharge end of the corresponding fluid-receiving chamber, of fluid-supplying means having supply-passages opening into said fluid-receiving chambers and disposed at a more acute angle to the plane of rotation of the wheel than said fluid-receiving chambers. 120

10. In a turbine motor, the combination, with a turbine wheel having fluid-receiving 125 chambers disposed transversely to its plane of rotation, and also having fluid-discharging chambers opening, respectively, into the fluid-receiving chambers and each of greater area

at its receiving end than the discharge end of the corresponding fluid-receiving chamber, of fluid-supplying means having supply-passages opening into said fluid-receiving chambers, and fluid-controlling means operative for opening or closing a predetermined number of said supply-passages.

11. In a turbine motor, the combination, with a turbine wheel having fluid-receiving chambers disposed transversely to its plane of rotation, and also having fluid-discharging chambers opening, respectively, into the fluid-receiving chambers and each of greater area at its receiving end than the discharge end of the corresponding fluid-receiving chamber, of fluid-supplying means having supply-passages opening into said fluid-receiving chambers and disposed obliquely and tangentially to the plane of rotation of the wheel.

12. In a turbine motor, the combination, with a turbine wheel having fluid-receiving chambers disposed transversely to its plane of rotation, and also having fluid-discharging chambers opening, respectively, into the fluid-receiving chambers and each of greater area at its receiving end than the discharge end of the corresponding fluid-receiving chamber, of fluid-supplying means having supply-passages opening into said fluid-receiving chambers and disposed obliquely to the plane of rotation of the wheel, and a shiftable valve having ports positioned to register with some or all of said supply-passages.

13. In a turbine motor, the combination, with a turbine wheel having fluid-receiving chambers disposed transversely to its plane of rotation, and also having fluid-discharging chambers opening, respectively, into the fluid-receiving chambers and each of greater area at its receiving end than the discharge end of the corresponding fluid-receiving chamber, of a casing; a fluid-chest in said casing and having a fluid-receiving opening and also having supply-passages opening into said fluid-receiving chambers and disposed obliquely to the plane of rotation of the wheel; and a circular cut-off valve mounted to turn in said chest and having an inlet-opening communicating with the supply and also having sets of supply-ports in position to communicate with some or all of said supply-passages.

14. In a turbine motor, the combination, with a turbine wheel having fluid-receiving chambers disposed transversely to its plane of rotation, and also having fluid-discharging chambers opening, respectively, into the fluid-receiving chambers and each of greater area at its receiving end than the discharge end of the corresponding fluid-receiving chamber, of a casing; a fluid-chest in said casing and having a fluid-receiving opening and also having supply-passages opening into said fluid-receiving chambers and disposed obliquely to the plane of rotation of the wheel; a circular cut-off valve mounted to turn in

said chest and having an inlet-opening communicating with the supply, and also having sets of supply-ports in position to communicate with some or all of said supply-passages; 7c a ball-bearing for said valve; and means for turning the latter.

15. In a turbine motor, the combination, with a turbine wheel having fluid-receiving and fluid-discharging chambers, of fluid-supplying means, and a fluid-controlling valve having two dissimilar sets of supply-ports in position to coöperate alternatively with the fluid-supplying means to open or close communication from all of the supply-ports of 8c either set simultaneously to some or all of the fluid-receiving chambers.

16. In a turbine motor, the combination, with a turbine wheel having fluid-receiving and fluid-discharging chambers, of fluid-supplying means having a plurality of supply-passages opening into said fluid-receiving chambers, and a fluid-controlling valve having two dissimilar sets of supply-ports in position to coöperate alternatively with the supply-passages to open or close communication from all of the supply-ports of either set simultaneously to some or all of said supply-passages.

17. In a turbine motor, the combination, with a turbine wheel having fluid-receiving and fluid-discharging chambers, of fluid-supplying means having a plurality of supply-passages opening into said fluid-receiving chambers, and a reciprocatory cut-off valve having two dissimilar sets of supply-ports in position to coöperate alternatively with the supply-passages to open or close communication from all of the supply-ports of either set simultaneously to some or all of said supply-passages.

18. In a turbine motor, the combination, with a turbine wheel having fluid-receiving and fluid-discharging chambers, of fluid-supplying means having a plurality of supply-passages opening into said fluid-receiving chambers, and an oscillatory cut-off valve having two dissimilar sets of supply-ports in position to coöperate alternatively with said supply-passages to open or close communication to some or all of such passages.

19. In a turbine motor, the combination, with a turbine wheel having fluid-receiving and fluid-discharging chambers, of fluid-supplying means having a plurality of supply-passages opening into said fluid-receiving chambers; a fluid-chest having an annular fluid-space; and an annular cut-off valve in said chest and having a plurality of supply-ports in position to open or close communication to some or all of said supply-passages.

20. In a turbine motor, the combination, with a turbine wheel having fluid-receiving and fluid-discharging chambers, of fluid-supplying means having a plurality of supply-passages opening into said fluid-receiving chambers; a fluid-chest having an annular

fluid-space; and an oscillatory annular cut-off valve in said chest and having a plurality of supply-ports leading from its annular space and in position to open or close communication to some or all of said supply-passages.

21. In a turbine motor, the combination, with a turbine wheel having fluid-receiving and fluid-discharging chambers, of fluid-supplying means; fluid-controlling means having a plurality of supply-ports in position to open or close communication between the fluid-supplying means and some or all of the fluid-receiving chambers; and a governor controlled by said turbine wheel and governing the operation of said fluid-controlling means.

22. In a turbine motor, the combination, with a turbine wheel having fluid-receiving and fluid-discharging chambers, of fluid-supplying means; an oscillatory cut-off valve having a plurality of supply-ports in position to open or close communication between the fluid-supplying means and some or all of the fluid-receiving chambers; and a governor controlled by said turbine wheel and operatively connected with said valve.

23. In a turbine motor, the combination, with a turbine wheel having fluid-receiving and fluid-discharging chambers, of fluid-supplying means; fluid-controlling means shiftable between two extreme positions and having a plurality of supply-ports in position to open or close communication between the fluid-supplying means and some or all of the fluid-receiving chambers; and a governor controlled by said turbine wheel and operative for shifting the fluid-controlling means automatically between its two extreme positions.

24. A turbine wheel embodying two connected wheel-sections having dissimilar reg-

istering fluid-receiving and fluid-discharging chambers, respectively.

25. A turbine wheel embodying two connected wheel-sections lying side by side and having dissimilar registering transverse fluid-receiving and fluid-discharging chambers, respectively.

26. A turbine wheel embodying two connected wheel-sections having dissimilar registering fluid-receiving and fluid-discharging chambers respectively intersecting the peripheries of said wheel-sections.

27. A turbine wheel embodying two connected wheel-sections having dissimilar registering fluid-receiving and fluid-discharging chambers respectively intersecting the peripheries of said wheel-sections, and a rim encircling the peripheries of said wheel-sections.

28. A turbine wheel embodying two connected circular webs of the same diameter lying side by side and having dissimilar oppositely-inclined registering fluid-receiving and fluid-discharging chambers respectively disposed obliquely to the plane of rotation of the wheel and intersecting the peripheries of said webs, and a circular rim shrunk around and encircling the peripheries of said webs.

29. In a turbine motor, the combination, with a main shaft, of collars secured to said shaft and formed with lugs and recesses; springs held on said shaft and engaging at their opposite ends the walls of the recesses in the collars; and a turbine wheel loosely mounted on said shaft and engaged by said springs and said lugs of the collars.

NILS NILSSON.
